JOHN P. McCARTY, OF OAKLAND, AND KENDALL DOUGLAS, OF SAN FRANCISCO, CALIFORNIA, ASSIGNEES, BY MESNE ASSIGNMENTS, TO UNIVERSAL WIRELESS TELEPHONE AND TELEGRAPH COMPANY, OF LOS ANGELES, CALIFORNIA, A CORPORATION OF CALIFORNIA.

METHOD AND APPARATUS FOR WIRELESS TELEPHONY.

1,205,365.

Specification of Letters Patent. Patented Nov. 21, 1916.

Application filed March 6, 1912, Serial No. 682,016. Renewed September 30, 1916. Serial No. 123,197.

To all whom it may concern:

Be it known that we, JOHN P. McCARTY, of the city of Oakland, county of Alameda, State of California, and KENDALL DOUGLAS, of the city and county of San Francisco, State of California, both citizens of the United States, have invented certain new and useful Improvements in Methods and Apparatus for Wireless Telephony, of which the following is a specification.

Our invention relates to the art of wireless telephony and especially to that branch of the art known as spark telephony.

Attempts to use the spark system for telephonic transmission have hitherto met with failure unless enormously high frequency alternators were employed, and such alternators are exceedingly expensive, of low efficiency, and for many reasons impractical.

The primary object of our invention is to provide a new and useful method and apparatus for spark telephony, using comparatively, very low frequency alternating currents.

We have discovered that spark produced damped waves of comparatively, very low alternating frequency may be used for telephony, if said waves be suppressed during the moment of silence, and emitted directly in correspondence with speech waves.

It is the object of our invention to provide a new and useful method and apparatus embodying our discovery, for transmitting speech by wireless telephony, wherein, although using continually produced oscillations, damped or undamped, there shall be effective radiation only during the time of vocal vibrations; and with the said object in view, our invention consists in continually producing oscillations in an oscillation circuit, suppressing the radiation in an associated radiation circuit, and directly radiating energy by operating the microphone transmitter.

It also consists in apparatus for continually producing oscillations in an oscillation circuit, for suppressing radiation in an associated radiation circuit, and for directly radiating energy by operating a microphone transmitter.

It also consists in a method of transmitting speech by wireless telephony, by con-

tinually producing oscillations in an oscillation circuit, suppressing the radiation in an associated radiation circuit, and emitting radiative energy in waves directly corresponding in rate of emission, energy, and form, with the pitch, force and quality of speech waves.

It also consists in apparatus for practising said method.

It also consists in the novel parts, combinations and arrangements set forth in the following specification, particularly pointed out in the claims, and illustrated in the accompanying drawing, of which—

Figure 1 is a diagrammatic view of a transmitting wireless telephone system, showing the initial arrangement of apparatus, with transmitter branch of radiation circuit open; and greatest radiation occurring; Fig. 2 is a similar view, showing the second step in arranging our apparatus, the transmitter branch of radiation circuit closed, the transmitter non-operated and radiation suppressed. Fig. 3 is a similar view, showing a third condition, in which the transmitter is operated and in which radiative energy is being emitted.

The same symbol of reference marks the same part in whichever view said part may appear.

Referring to the drawing, a radiation circuit *a* is provided, which includes the antenna wire 1, the variable inductance 2, the secondary 3 of the oscillation transformer *b*, the variable capacity 4, and the ground 5. A branch *c* of the radiation circuit is provided, which is grounded at one end 6, and contains a telephone transmitter *T*, which may consist of one or more microphone transmitters.

In Fig. 1 the branch circuit is shown as open at 7 and closed in the other figures. An ammeter 8 in the antenna is shown to indicate the change of radiation under the various conditions. An oscillation circuit *d* is associated with the radiation circuit in any well known manner, as though the oscillation transformer *b* by its connection with primary 9; and it also contains the spark gap *s*, variable condensers 10, and the secondary 11 of the transformer *f*. The condensers are shown as connected in multiple series instead of as a single equivalent ad-

justable condenser because the former arrangement tends to prevent the destructive flashing over between plates which is likely to occur under high pressure. An alternator 5 circuit *h* includes the source of alternating current 12, which is one of comparatively very low frequency, and primary 13 of transformer *f*.

In practising our method, we first place 10 our apparatus in the condition illustrated in Fig. 1, with the branch *c* open. We then tune the oscillation circuit *d* and radiation circuit *a* into complete syntony with each other, so that the maximum radiation is taking place, as indicated by the needle of the 15 ammeter in Fig. 1. When the state of syntony is attained we close branch *c*, as shown in Fig. 2; whereupon, not only is the radiation circuit, including its branch, thrown 20 out of tune with the oscillation circuit *d*, a condition which tends to suppress radiation, but whatever oscillations are created are practically confined in the closed circuit formed by the coils 2 and 3, the condenser 4 25 and branch *c*, wherefore they are denominated suppressed radiation. Under such conditions the needle of the ammeter approximates zero, which indicates that the effective radiation is suppressed. Such condition is maintained during the moments of 30 silence.

Referring now to Fig. 3, when talking occurs, radiative energy is emitted, as shown by the ammeter in the antenna. The cause 35 of such emission is the change in the effective resistance of the telephone transmitter *T*, which, as it causes branch *c* to approach or recede from the condition illustrated in Fig. 1, produces a corresponding emission 40 of radiative energy. It is obvious that the radiative energy will be emitted in waves following the form, amplitude and rate of succession of speech waves, and that during the intervals between the speech waves, the 45 radiation is suppressed.

It is obvious that our method is equally applicable to undamped oscillation systems. The radiation circuit in such systems would be tuned as in Fig. 1 with the oscillation circuit, the radiation suppressed as in Fig. 2 50 and emitted as in Fig. 3. Whether damped or undamped oscillations are used, our method produces radiation in correspondence with speech waves.

We are aware that microphone transmitters located in a branch shunting the secondary of an oscillation transformer have 55 been used; but in such cases the radiation circuit, including the branch, has been tuned to emit the greatest radiation when 60 no talking is taking place. The mode of operation of such devices is to interrupt the continually radiated energy, as distinguished from our method, which suppresses 65 the radiation, and sends it out in waves

directly corresponding with the changes of resistance in the shunt, which changes are produced by vocally vibrating the microphone transmitter.

Because our radiation is suppressed at 70 the moments when the microphone transmitter is not operating, disturbances due to such radiation at such moments cannot take place. Moments when the microphone transmitter is inactive occur within the compass of spoken words, between the syllables, and in the intervals separating the words. Such moments are normal constituents of speech, and cannot be interfered with if clearness is to be preserved. We claim for 75 our system that it will not interfere with the moments of silence; for even the undamped oscillation systems tend to interfere when the arc varies in character. We have found that the alternating impulses of the frequency used in our method have no detrimental effects on the articulation. It is to be observed that the branch circuit is one practically without inductance. The necessary adjustments of inductances and capacities to secure the suppression of the radiation may readily be made by the adjustable condensers and coils shown in the drawing. By "no radiation" it is to be understood 80 an amount of radiation so small as to 85 be negligible, approaching zero near enough for practical purposes.

Having described our invention, what we claim as new and desire to secure by Letters Patent of the United States, modifications 90 within the scope of the claims being expressly reserved, is:

1. A method of transmitting speech by wireless telephony which consists in continually producing oscillations in an oscillation 105 circuit, deriving therefrom oscillations the radiation of which is suppressed in a radiation circuit, and emitting radiative energy from said circuit in direct correspondence with speech waves.

2. A method of transmitting speech by wireless telephony which consists in continually producing oscillations in an oscillation circuit, deriving therefrom oscillations in a radiation circuit, suppressing radiation 115 therefrom during moments of silence, and emitting waves of radiative energy in direct correspondence with speech waves.

3. Apparatus for transmitting speech by wireless telephony which consists in an oscillation circuit, means for continually producing oscillations therein, a radiation circuit associated therewith, means for deriving from said oscillation circuit oscillations the radiation of which is suppressed in said 125 radiation circuit, and means for emitting radiative energy in direct correspondence with speech waves.

4. Apparatus for transmitting speech by wireless telephony which consists in an oscil- 130

lation circuit, means for continually producing oscillations therein, a radiation circuit associated therewith, means for suppressing radiation in said radiation circuit during the moments of silence, and means for emitting waves of radiative energy in direct correspondence with speech waves.

5. Apparatus for transmitting speech by wireless telephony which consists in a radiation circuit, an associated continually operated oscillation circuit tuned thereto, a branch circuit for suppressing the radiation from said radiation circuit, and a microphone transmitter in said branch for transmitting radiative energy in correspondence with speech waves.

10. Apparatus for transmitting speech by wireless telephony which consists in a radiation circuit including a variable inductance coil and a variable condenser, an associated continually operated oscillation circuit tuned thereto, a branch circuit attached outside the inductance coil and condenser for suppressing radiation from said radiation circuit, and a microphone transmitter in said branch for transmitting radiative energy in correspondence with speech waves.

15. The method of transmitting sound by wireless telephony, which method comprises producing oscillations, normally suppress-

ing radiation of said oscillations, and effecting by sound waves the emission of radiative energy which emission consists of waves corresponding in form, amplitude and rate to said sound waves.

35. 8. In combination, an oscillatory circuit, a radiation circuit, means to suppress radiation in the radiation circuit when affected by sound waves to produce emission of radiative energy from the radiation circuit in waves corresponding in form, amplitude and rate to sound waves.

40. 9. In a wireless telephone system, a source from which alternating current is produced having a frequency of from one thousand 45 to four thousand, means for producing oscillations in an oscillation circuit, a radiation circuit associated therewith, means for suppressing radiations from said radiation circuit, and means for emitting radiative energy from said circuit in direct correspondence with speech waves.

45. In testimony whereof, we have hereunto signed our names in the presence of two witnesses this 29th day of February, 1912.

JOHN P. McCARTY.
KENDALL DOUGLAS.
